CLAIM

The ornamental design for the folding rigid box, as shown and described.

DESCRIPTION

FIG. 1 is a front-top perspective view showing my new design in a first configuration.

FIG. 2 is a left side view thereof in the first configuration. The right side view is a mirror image thereof.

FIG. 3 is a front view thereof in the first configuration. The rear view is a mirror image thereof.

FIG. 4 is a front view thereof in a second configuration.

FIG. 5 is a rear view thereof in the second configuration.

FIG. 6 is a top view thereof in the first configuration; and,

FIG. 7 is a bottom view thereof in the first configuration. The broken line portion of the figure drawings is included to show unclaimed subject matter only and forms no part of the claimed design.

1 Claim, 5 Drawing Sheets
